UNITED STATES PATENT OFFICE

ANTONINO DE SPUCHE, OF PALERMO, ITALY

METHOD OF PROPULSION BY SUCTION AND REPULSION

Application filed June 27, 1928, Serial No. 288,761, and in Italy July 7, 1927.

The present invention concerns improvements in those methods of propulsion applied to vehicles wholly or partly immersed into a fluid, wherein the fluid is sucked in from the 5 part of the bow, and then ejected after having run through a conduit which extends in the longitudinal direction of the vehicle.

By the application of the said methods of propulsion through suction and repulsion of 10 the fluid it has not been hitherto possible, however, to eliminate a serious drawback, which also occurs in the case of propulsion by wheel or by screw, and consisting in that the part of resistance due to the displacement of 15 the fluid during motion increases considerably with the square of the speed, and consequently the force necessary to overcome it increases approximately with the cube of the speed, so that, when high speeds are attained, 20 a further even slight increase of such speeds requires an enormous increase of the propelling power.

The object of the present invention is to eliminate the said inconvenience by practically reducing the advancing resistance only 25 to the part which depends from the friction of the fluid against the outer walls of the moving vehicle, and suppressing, on the contrary, the resistance due to the displacement of the 30 fluid, by utilizing the sucking action itself for the elimination of the frontal resistance.

In order to obtain this result, the following conditions are indispensable:

1. The fore part of the ship constituting 35 the tapered bow of the hull should be truncated and said hull should have an aperture therethrough equal in area to the remaining cross-sectional area between the hull and said aperture.

40 2. That starting from said aperture the hull, and, respectively, the immersed part of the same, should continue in a parallel form with constant cross-section, up to the point where the tapered portion of the stern starts 45 so that the water flows externally with threads parallel to the median longitudinal plane of the ship, not meeting with any other resistance than that of friction against the walls of the hull itself and without under- 50 going any lateral displacement.

3. That the said opening in the bow by means of a funnel-shaped part, be suitably connected to the longitudinal conduit through which the water must flow and in which is placed the device which produces its 55 circulation.

4. That as soon as the portion of conduit, in which the suction device is placed, has been passed, the water stream be divided in two separate veins by a suitably shaped distributing partition, which causes them to flow towards two lateral outlets from whence the discharge is performed.

5. That at the stern the ship be provided with a screw, the speed and pitch of which be regulated so as to produce a positive thrust when the ship advances with the maximum speed.

6. Finally it is necessary that the bow opening be protected by a casing formed of 70 a bow shaped grate, in order to avoid the introduction of foreign bodies, carried by the arriving current, into the interior of the conduit in which is placed the suction apparatus.

In the accompanying drawing which serves to schematically illustrate the structure of a ship furnished with propelling apparatus according to the present invention.

Fig. 1 is a front view in elevation, in correspondence with the bow inlet, the grate of the casing being omitted.

Fig. 2 is a top view showing the conduit with the suction screw and the propelling screw.

Fig. 3 is a view in vertical section of the same.

As will be seen from the drawings, the immersed portion of the hull 1 has parallel sides and constant cross-section, is truncated at the bow according to line AA, and ends at the stern with a tapered part 2, which is connected to the rest of the hull in the usual manner.

Above this immersed part extends the 95 dead work 3 designed to emerge completely in normal conditions, and which as a whole presents the shape of an ordinary hull.

In the truncated section the immersed part is completely open, and the aperture has a 100

cross-section equal to the truncated cross-section. This large opening is connected by means of a funnel-shaped piece 4 with the front mouth-piece, in the plane of section BB, of a horizontal longitudinal conduit 5, in the interior of which is disposed a suction apparatus, which sucks the water from the fore opening in section AA to discharge it then further back and laterally.

10 In the example schematically represented by the drawing it is supposed that this suction device consists of a simple or double screw 6, conveniently shaped and carried by shaft 7.

15 Past the suction device the longitudinal conduit 5 bifurcates in two branches 8', 8'', into which the water stream is introduced by means of a distributing partition 9, conveniently shaped so as to prevent sudden 75 shocks and the formation of eddies. The two said branches 8', 8'' discharge symmetrically at the two sides of the vessel where the water issues from apertures 9', 9''.

20 At the stern is arranged a propelling screw 10, which could be mounted on a shaft of its own, but it is preferably carried by the same shaft 7 which carries the suction screw as shown in the drawing.

25 At the bow is disposed in front of the inlet 30 of section AA a protecting cage or grate 11 of iron bars, having as a whole the shape of a tapered bow portion, the longitudinal as well as the transversal connecting bars being arranged so as to meet the arriving water stream 35 slantwise, thus diminishing the resistance.

After these preliminary remarks it is easy to understand the working of the system.

30 By turning the suction screw, the water rushes in from the bow, enters the large inlet 40 and accelerating its motion in flowing through the funnel-shaped portion it arrives with its maximum speed in the longitudinal conduit through which it flows discharging from the two lateral apertures.

45 In order to obtain the best possible effect, namely a minimum resistance to the advancement, it is necessary that the water enters the great aperture with the same speed relative to the hull with which the hull itself advances 50 in respect to the water in which it is immersed. When this condition is attained the water which comes from the bow flows along the sides of the hull with parallel threads without any resistance of displacement, so 55 that the resistance to the vessel's advancement is reduced only to that of the friction of the water on the outer walls of the hull itself.

60 It is precisely in order to obtain this condition that, together with the fore-opening being as large as the main section, has been arranged the rear propelling screw 10, by means of which it is possible to maintain the speed of the water through the fore-opening equal to the vessel's speed of advancement.

65 It is clear that by conveniently regulating

the pitch and the surface of the propelling screw, it will be easy to constantly maintain this result; mounting the propelling screw 10 on the same shaft as the suction screw as shown in the drawing, makes it essential that the propelling screw have a greater pitch than the suction screw. Moreover, although it is shown in the drawing that the suction of the water is performed by means of a screw, it is clear that, instead of a screw, a centrifugal pump or some other suitable apparatus may be used.

70 Lastly it will be understood that if the two lateral mouths 9' and 9'' are provided with bulkheads permitting the closure of one or the other mouth, they may act in combination with the rudder in order to render more efficient the steering of the ship.

Claims—

1. A ship propelled by reaction comprising a normally submerged hull having a truncated bow, a forward part of constant cross section followed by a stern portion tapered in the usual way, a longitudinal conduit mounted within the portion of said hull having constant cross section, a funnel shaped piece integral with the forward end of said conduit and the truncated bow of said hull, a vertical distributing partition at the rear end of said conduit, forming stream line lateral discharges therefor which open at mid length in the portion of the hull of constant cross section and suction means mounted within said conduit.

2. A ship propelled by reaction comprising a normally submerged hull having a truncated bow, a forward part of constant cross section followed by a stern portion tapered in the usual way, a longitudinal conduit mounted within the portion of said hull having constant cross section, a funnel shaped piece integral with the forward end of said conduit and the truncated bow of said hull, a vertical distributing partition at the rear end of said conduit forming stream line lateral discharges therefor which open at mid length in the portion of the hull of constant cross section, suction means mounted within said conduit and a propelling screw mounted on the rear of said hull.

3. A ship propelled by reaction comprising a normally submerged hull having a truncated bow, a forward part of constant cross section followed by a stern portion tapered in the usual way, a tapered bow-shaped protecting grate positioned on said truncated bow, a longitudinal conduit mounted within the portion of said hull having constant cross section, a funnel shaped piece integral with the forward end of said conduit and the truncated bow of said hull, a vertical distributing partition at the rear end of said conduit forming stream line lateral discharges therefor which open at mid length in the portion of the hull of constant cross section, a rotating

shaft coaxially mounted within said conduit extending for the whole length of the hull up to the stern carrying a suction screw and a propelling screw at the rear of said hull also mounted on said rotating shaft.

In testimony whereof I have affixed my signature at Rome, Italy, this eighth day of June, 1928.
